United States Patent Office

Des. 203,022
Patented Nov. 23, 1965

203,022

COSMETIC CASE OR SIMILAR ARTICLE

Robert Mayer, Scarsdale, N.Y., assignor to Eller Associates, Inc., New York, N.Y., a corporation of New York

Filed Aug. 26, 1964, Ser. No. 81,462

Term of patent 3½ years

(Cl. D87—5)

Fig. 1

Fig. 2

Fig. 3

Fig. 4

Fig. 5

Fig. 6

FIGURE 1 is a top plan view of a cosmetic case or similar article showing my new design in closed condition;

The bottom of the case, not shown, is substantially identical to the top of the case.

I claim:

The ornamental design for a cosmetic case or similar article, substantially as shown and described.
